UNITED STATES PATENT OFFICE.

CHRISTIAN L. BERGER, OF BOSTON, MASSACHUSETTS.

LATERAL ADJUSTER FOR SURVEYING INSTRUMENTS.

SPECIFICATION forming part of Letters Patent No. 696,401, dated April 1, 1902.

Application filed September 25, 1901. Serial No. 76,516. (No model.)

To all whom it may concern:

Be it known that I, CHRISTIAN L. BERGER, a citizen of the United States, residing at Boston, county of Suffolk, State of Massachusetts, have invented an Improvement in Lateral Adjusters for Surveying Instruments, of which the following description, in connection with the accompanying drawings, is a specification, like letters on the drawings representing like parts.

My invention relates to the base portion of a surveying instrument, and is more particularly adapted to mining-transits, being intended to provide means for quickly shifting the transit horizontally after it has been properly leveled and adjusted without disturbing said adjustment.

In general, surveying instruments have been moved laterally relatively to the tripod in two ways, one way being to move the upper part of the instrument relatively to the base and the other way being to move the instrument and its base bodily, the former, however, resulting in placing the telescope and adjacent parts eccentric to the vertical axis of the instrument, and hence in that respect in improper position for usual work, especially mining-work, and the latter, although not subject to the last-mentioned objection, being, however, of such construction that precision of movement and maintenance of the instrument adjustments could not be relied upon. Accordingly I have devised the special means, which are more fully set forth in the following description, for enabling the operator to be sure at all times that when once adjusted and leveled the instrument, although moved laterally, will maintain its said adjustments, and to know also that the lateral movement takes place with perfect precision, as intended.

In the drawings, in which I have illustrated a preferred embodiment of my invention, Figure 1 is a perspective view of a usual surveying instrument having one form of my invention applied thereto. Fig. 2 is an enlarged central vertical section of the most complete form of my invention. Fig. 3 is a right-hand side elevation thereof, parts being broken away. Fig. 4 is a sectional view similar to Fig. 2, showing a simple form of the invention. Fig. 5 is a vertical cross-sectional

detail on the line 5, Fig. 4; and Fig. 6 is a bottom plan view, parts being broken away.

For convenience of illustration I have shown a portion of a usual transit A, mounted on a usual tripod a, the former containing a usual post a', leveling-screws a², base-plate a³, centrally apertured at a⁴ to permit usual lateral adjustment of the base a⁵ of the supporting-post, and the tripod is provided at its upper end in usual manner with a threaded shoulder or ring a⁶. Preferably the threads of the plate a³ correspond to the threads of the ring a⁶, so that when desired the intermediate device (which constitutes my invention) may be removed and the plate a³ may be screwed onto the ring a⁶ in its usual position. My invention, as already stated, resides in providing special means between the plate a³ and the tripod-ring a⁶ for accurately shifting the superposed instrument one way or another precisely as required, this feature being of particular value in mining-work below ground, although I do not limit the same to this use.

In mine-surveying the work is sometimes done in the dark or partial darkness and the leveling of the instrument by the aid of a faint light, and proper adjustment thereof consumes a great deal of time, patience, and skill, so that when it is once accomplished it is of peculiar advantage to retain the adjustments. For example, in getting the range of two plumb-lines, which may be suspended in usual manner from the top of a vertical shaft, the plumb-bobs being held still in buckets of molasses or in other well-known manner, the surveyor first sets up his tripod as nearly in correct position as he can judge and as may be permitted by the situation. He then gets the instrument more accurately in line by means of the telescope, and, having done so, levels the instrument; but in doing so he throws the telescope out of line. If, now, the instrument is of the ordinary kind, as shown in the upper portion of Fig. 1, he must slightly loosen the leveling-screws a², so as to shift the instrument-post a⁵ relatively to the plate a³, and thereby bring the telescope back approximately into line. This, however, has destroyed the accurate leveling of the instrument, and therefore it must again be leveled. Bearing in mind that this

all takes place in comparative darkness with only at least a glimmer of light, it will at once be seen that this destroying of the proper leveling of the instrument becomes very serious.

5 To prevent this difficulty, I provide a guide-plate b , provided centrally with threads b' , fitting the ring a^6 , so that it may be screwed rigidly in place, and on this plate I mount a slide-plate b^2 , which may be provided in the 10 simpler form of my invention with an annular flange b^8 , threaded to correspond to the ring a^6 for receiving the base-plate a^3 of the instrument. In this case the instrument has a lateral movement in one direction by reason of the slide-plate b^2 moving over the guide-plate b . Preferably, however, a lateral movement is provided also in an opposite horizontal direction, this result being accomplished, as herein shown, by providing on the 15 upper side of the slide-plate b^2 a guideway b^3 , similar in general construction to the guide-plate b , and on this guideway b^3 is fitted a second slide-plate b^4 , which is provided with an annular threaded flange b^5 for receiving 20 the base-ring a^3 of the instrument.

Referring further to the constructional details of the device, it will be seen that the edges of the guides b b^3 are beveled or oblique and that the slide-surfaces of the plates b^2 b^4 , 25 which bear on said oblique surfaces, are also correspondingly oblique, thereby insuring a permanently accurate fit and also providing a construction which makes it impossible for dirt or moisture to reach the bearing-surfaces.

30 Absolute accuracy of adjustment is secured by providing bearing-screws b^6 in the slide-plates to bear against the adjacent top surface of the guides, as clearly shown in Figs. 1 and 5.

35 On its under side the slide-plate b^2 is provided with retaining-screws b^7 , which engage the under sides of the adjacent edges of the plate b , and for the same purpose screws b^8 are provided to engage a narrow flange b^9 of 40 the plate b^4 when the latter is employed. In this manner the instrument may be kept in true position precisely as required. At one or both ends, the latter giving the greatest precision, I provide operating-screws b^9 , 45 working in the threaded ends b^{10} of the plates b and b^4 and bearing against apertured projections b^{12} from the superposed slides, these screws being provided with suitable thumb-nuts or other turning means b^{13} . Preferably, 50 also, each screw carries an accurately-spaced indicator b^{14} , said indicator, as herein shown, having points b^{15} , located forty-five degrees from each other, for coöperation with a projection b^{16} on the adjacent sliding member, 55 so that in the comparative darkness the operator may know precisely how far to one side or the other he shifts his instrument simply by feeling the number of points of the indicator which he turns past the projection b^{16} .

60 From the above description the operation of my improved lateral adjuster will be readily understood. The operator wishing to

do underground work simply takes his usual instrument and separates the upper portion at the base-plate a^3 from the tripod and then 70 screws onto the latter my attachment and places the upper part of the instrument on top thereof, screwing the base-plate a^3 on the flange b^5 in case the more complete form of the device is used or on the ring b^8 in case 75 the simpler form shown in Fig. 4 is employed. Having adjusted his instrument in usual manner, as required, he now shifts the entire instrument with precision to the left or right, forward or backward, as the case may be, by 80 simultaneously turning in reverse directions the opposite thumb-screws b^{13} , or one of them only in case the other is omitted, and by counting the number of points b^{15} which turn past his thumb resting on the projection b^{16} he 85 knows the exact distance to which the instrument is shifted. In case he should desire to tip the instrument slightly one way or the other or take up any wear of parts, he correspondingly adjusts the screws b^6 or such of 90 them as may require it.

While I have herein shown and described my invention in all its preferred details, I wish it understood that, excepting as otherwise required in the claims, I do not limit 95 my invention thereto, as many changes in construction and arrangement of parts may be resorted to within the spirit and scope of my invention.

Having described my invention, what I 100 claim as new, and desire to secure by Letters Patent of the United States, is—

1. A lateral adjuster for mining-transits, comprising a guide-plate provided centrally with means for rigidly securing the same on 105 a usual tripod, a slide-plate mounted thereon, said two plates being mutually provided with coöperating ways for maintaining accurate direction of movement, a thumb-screw in engagement with said two plates for accurately 110 moving the top plate on the bottom plate, and means for mounting above said top plate a mining-transit.

2. A lateral adjuster for mining-transits, comprising a guide-plate provided centrally 115 with means for rigidly securing the same on a usual tripod, a slide-plate mounted thereon, said two plates being mutually provided with coöperating ways for maintaining accurate direction of movement, a thumb-screw in engagement with said two plates for accurately 120 moving the top plate on the bottom plate, said top plate being provided on its upper side with guideways extending transversely to the direction of movement of said plate on 125 the guide-plate below, a topmost guide-plate mounted on said guideways and shaped on its under surface to fit on said guideways, means for moving said topmost plate on said guideways, and means above said topmost 130 plate for securing thereto the instrument proper.

3. In a mining-transit, means located between the instrument proper and the tripod

for shifting the instrument bodily in one direction in a horizontal plane, and means for similarly shifting said instrument bodily in a direction transversely thereto.

5 4. In a mining-transit, means located between the instrument proper and the tripod for shifting the instrument laterally in a horizontal plane, and means angularly shaped to indicate, by feeling, the extent of said lateral movement.

10 5. In a mining-transit, means located between the instrument proper and the tripod for shifting the instrument laterally in a horizontal plane, said means including a stationary part, a thumb-screw, and an indicator rotative therewith containing coarse spacing-points for enabling the operator to tell, by feeling, the extent of rotation of said screw by reference to a relatively stationary part.

15 6. A lateral adjuster for mining-transits, comprising a guide-plate provided centrally with means for rigidly securing the same on a usual tripod, a slide-plate mounted thereon, said two plates being mutually provided with

20 coöperating ways for maintaining accurate direction of movement, a thumb-screw in engagement with said two plates for accurately moving the top plate on the bottom plate, an indicator, capable of readily indicating by

25 30 feeling, carried by said thumb-screw for indicating the extent of rotation thereof, and means for mounting above said top plate a mining-transit.

35 7. A lateral adjuster for mining-transits, comprising a guide-plate provided centrally with means for rigidly securing the same on a usual tripod, a slide-plate mounted thereon, said two plates being mutually provided with coöperating ways for maintaining accurate

40 direction of movement, a thumb-screw at each

end of and in engagement with said two plates for accurately moving the top plate on the bottom plate, and means for mounting above said top plate a mining-transit.

8. A lateral adjuster for mining-transits, 45 comprising a guide-plate provided centrally with means for rigidly securing the same on a usual tripod, a slide-plate mounted thereon, said guide-plate having its opposite side edges beveled, and said slide-plate having at its opposite edges depending portions beveled on their inner sides to rest on the beveled edges of the guide-plate, means retaining said two plates permanently together, independently-operable adjusting devices for adjusting the 50 bearing-surfaces of the two plates with relation to each other, positive means for accurately sliding the top plate on the bottom plate, and means for mounting the instrument proper above the top plate. 55

9. A lateral adjuster for mining-transits, comprising a guide-plate provided centrally with means for rigidly securing the same on a usual tripod, a slide-plate mounted to slide on said guide-plate, guiding means for mutually guiding said plates in relative longitudinal movement, a transit proper mounted on said slide-plate and comprising usual telescope-leveling devices, &c., and means for positively moving the top plate on the bottom plate to any predetermined extent required. 60 65 70

In testimony whereof I have signed my name to this specification in the presence of two subscribing witnesses.
